(57) **CLAIM**

The ornamental design for ring as shown and described.

DESCRIPTION

FIG. 1 is a front perspective view of ring showing our new design;

FIG. 2 is a back perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

1 Claim, 8 Drawing Sheets# US D1,062,506 S
